CLAIM

The ornamental design for a carrying case for a compact disc player and accessories, as shown and described.

DESCRIPTION

FIG. 1 is a front elevational view of a carrying case for a compact disc player and accessories showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a front right perspective view thereof.

The broken lines shown throughout the views are understood to represent stitching.
